(57) **CLAIM**

The ornamental design for a spirit level (FL-S878), as shown and described.

DESCRIPTION

FIG. 1 is a perspective view (ISO view 01) of a spirit level (FL-S878) showing the new design;

FIG. 2 is another perspective view (ISO view 02) thereof;

FIG. 3 is a front side view thereof;

FIG. 4 is a back side view thereof;

FIG. 5 is a left side view thereof;

FIG. 6 is a right side view thereof;

FIG. 7 is a top view thereof; and,

FIG. 8 is a bottom view thereof.

The broken lines in the drawings depict environmental subject matter only and form no part of the claimed design.
